Des. 190,908
Patented July 18, 1961

190,908

MULTIPLE SEATING UNIT

George Kasparian, 9562 La Tijera Blvd.,
Los Angeles, Calif.

Filed July 5, 1960, Ser. No. 61,208

Term of patent 14 years

(Cl. D15—11)

Fig. 4

Fig. 5

FIGURE 1 is a perspective view of a multiple seating unit showing my new design;

FIGURE 2 is a front elevational view of the multiple seating unit shown in FIGURE 1;

FIGURE 3 is a side elevational view thereof;

FIGURE 4 is a rear elevational view thereof; and

FIGURE 5 is a top plan view thereof.

I claim:

The ornamental design for a multiple seating unit, as shown.
